UNITED STATES PATENT OFFICE.

CLARENCE W. FULLER, OF YONKERS, NEW YORK.

OPERATING MECHANISM FOR ROTARY TOOLS.

1,229,603.

Specification of Letters Patent. Patented June 12, 1917.

Application filed July 29, 1916. Serial No. 111,973.

To all whom it may concern:

Be it known that I, CLARENCE W. FULLER, a citizen of the United States, residing at Yonkers, in the county of Westchester and

5 State of New York, have invented certain new and useful Improvements in Operating Mechanism for Rotary Tools; and I do hereby declare the following to be a full, clear, and exact description of the invention, such 10 as will enable others skilled in the art to which it appertains to make and use the same.

This invention is a device designed more particularly for cleaning teeth, although capable of other uses, wherein a brushing element may be rotated in a plurality of directions.

A purpose of the invention is to provide a removable brushing element which is capable 20 of rotation in a plurality of directions effected by means controlled at will.

Broadly stated, the invention comprises a rotatable member, such as a shaft, having a plurality of clutch devices which alternately 25 operate to rotate the shaft in opposite directions, and means carried by the shaft such as a tool end, to engage a suitable tool, such as a brushing or scrubbing element which may be removably mounted on the tool end.

30 Other objects and advantages of the invention will become apparent from the following detail description taken in connection with the accompanying drawings, wherein an embodiment of the invention is shown, but it is to be understood that the construction therein set forth is for the purposes of illustration only, and not as defining the limits of the invention.

In the drawings:—

40 Fig. 1 is a plan view of the device with the tool or brush element removed.

Fig. 2 is a detail view of one clutch member showing a pivotal clutch actuating device.

45 Fig. 3 is a detail view of another clutch member disclosing a slidable clutch actuating device.

Fig. 4 is a detail view, partly in section, of a brushing element mounted upon a ferrule which is adapted to be positioned on the tool end of the device.

Fig. 5 is a detail view of the tool end disclosing a retaining slot.

Fig. 6 is an end view of the ferrule.

55 In the construction shown in the accompanying drawings, the shaft is rotated by

manually operated means. It is rotated in reverse directions by novel clutch members which are successively operated by the means which rotate the shaft.

In the construction shown, a frame is employed having the sides 1, 2 and ends 3, 4 formed in a single piece. The shaft 5 is journaled in the ends 3, 4, respectively. This shaft is designed to carry a tool end of any 60 suitable form, shown in the drawings as an elongated member which is preferably of soft metal or any other material, having a large end 6 serving as an abutment and an end 7 of lesser diameter than the end 6. The 65 end 7 may be provided with a plurality of longitudinal grooves 8 which may be of any desired depth and preferably slightly deeper at the end 7 to facilitate the application of a tool to the end. The grooves may terminate 70 in an abutment.

Cooperating with the tool end of the shaft is a ferrule 10 which may be of any suitable material, and is preferably of a diameter sufficiently great to fit over the end 7 of the 75 tool end, and to be moved along the reduced portion thereof until an end of the ferrule abuts against the thicker portion 6. This ferrule is shown provided with a plurality of retaining devices formed by slitting the 80 material as at 11 and depressing the cut material inwardly. The slits are preferably oppositely positioned, and in the structure disclosed, four of them are shown in the ferrule 10, two upon each side thereof.

The ferrule 10 is designed to accommodate the operating tool, which in the instance shown, is a brushing element indicated at 12, the bristles of which are mounted upon a stem which terminates in bifurcated ends 13. 95 These ends 13 may be in the form of wires positioned parallel to each other, and designed to be passed between the depressed portion 14 of the ferrule 10 and the main body of the ferrule, whereby when the tool 100 ends 13 of the bifurcated member are passed through the ferrule to be engaged by the depressed portions 14 on opposite sides of the ferrule, a brush 12 will be positively rotated with the ferrule when applied upon the 105 spindle, and at the same time, may be quickly applied to the ferrule or removed therefrom, when the ferrule has been dismounted from the tool end 7.

In applying the ferrule 10 to the tool end 110 7, the ends 13 are designed to be positioned to register with the grooves 8 and as the

ferrule 10 is pressed toward the enlarged end 6, the outer ends 15 of the bifurcated members 13 will be directed toward the ends 9 of the grooves 8, and thereby cause the ends 15 to be slightly flexed outwardly and held between the material of the member 6 and the material of the ferrule 10 to thereby prevent the accidental disengagement of the ferrule from the tool end.

10 The spindle is provided with an upper clutch shown comprised of a plurality of members 16, 17, each of which is shown with 15 coöperating teeth indicated at 18. The member 16 is preferably splined or otherwise secured to the spindle 5 for rotating the spindle when the member 17 has been actuated by any suitable means. Positioned adjacent the member 17 is a clutch actuating member indicated at 19, which is pivotally mounted at 20 to a side 1 of the frame. This clutch actuating member is shown provided with a pin 21 which is adapted to engage an end 22 of the clutch member 17 to move said member 17 toward the member 16 when the clutch actuating device is moved upon its pivot 20 to bring the pin 21 into engagement with the face 22 of the clutch member. The clutch member 17 is provided with a drum 23 upon which may be wound a suitable cable indicated at 24, which cable is shown passing through an aperture 25 of the actuating member 19 and 29 extending through an aperture 26 in an end 4 of the frame, after which, the cable 24 is secured to a ring 27 or other device for conveniently operating the cable. The clutch member 17 is rotated in one direction by drawing upon the cable 24, which causes the clutch actuating member 19 to move 40 downwardly upon its pivot 20 until the pin 21 engages the end 22 of the clutch member 17 to move the clutch member 17 into engagement with the clutch member 16; thereafter, the further movement of the drum 23 by drawing upon the cable 24, will cause the spindle 5 to rotate in one direction. The arrangement is such that upon release of the cable the clutch members will automatically become disengaged. A coil spring 50 28 may be employed to rotate the drum in an opposite direction to rewind the cable upon the drum 23, after disengagement of the clutch members, it being understood that the spring 28 is connected with the end 55 22 of the clutch member 17 in any suitable manner, and also anchored to the frame members either 1 or 2.

At the opposite end of the frame there is shown another clutch having members 29 and 30, said clutch being provided to operate the spindle reversely to the clutch formed by members 16 and 17. Clutch member 29 is secured directly to the spindle for rotation therewith, while clutch member 30 is loosely mounted upon the spindle.

These members are provided with teeth 31 whereby they may be engaged for coöperative movement in one direction, as has been described with relation to the other clutch formed by members 16 and 17. Clutch member 30 is provided with a drum 32 around which may be wound a cable 33 which passes through a slide block 34 having a pin 35, said slide block being mounted upon a side 2 of the frame. The cable 33 thereafter 70 extends through the end 4 of the frame and terminates in a ring 36, or other suitable device. Coöperating with the drum clutch member 30 is a spring 37 which is connected to said drum clutch member and to the frame for rotating the drum clutch member in a direction opposite to that in which it is rotated by drawing upon the cable by means of the ring 36. In this clutch, when the ring 36 is drawn away from the frame end 4, the cable will draw upon the slide block 34 by reason of the fact that it is passed through an aperture in said block and thereafter extends longitudinally of the block toward said ring, such construction causing the block to be moved toward the end 4 of the frame. This movement of the block causes the pin 35 to engage a face 38 of the drum clutch member to move said member toward the fixed clutch member 29 until the teeth 31 of said members coöperate to move the clutch and the spindle in the direction actuated by the pull upon the cable 33. When the pull is released from the cable 33, the clutch members are automatically disengaged and the spring 37 operates to move the clutch drum in an opposite direction and to return the cable upon the drum.

In operation, the brush element 12 may be applied to the tool end of the spindle, and inserted into the mouth so that the brushing element will engage the teeth to brush them longitudinally of each tooth, instead of transversely of the teeth, as is the usual method of brushing the teeth by the layman when using the ordinary bristle end brush. By having the plurality of pull devices, the brushing element may be rotated in one direction for the teeth of one group, or in the opposite direction for the teeth of another group, so that the teeth may be brushed from the bottom to the upper or biting surface thereof, without the disagreeable feature of having the brush rotate in the reverse direction to cause the substance taken from the teeth to be brushed back into the mouth. This is effected by drawing first upon ring 27 to move the cable of clutch members 16 and 17, which will rotate the brush in one direction, and thereafter drawing upon the ring 36 to operate the clutch members 29, 30 to rotate the brush 12 in the opposite direction.

It is obvious that various changes in the

form and proportion of parts may be made without departing from the spirit of the invention, such, for example, as the clutch actuating devices, or the means to move the 5 spindle, other than that shown, as the rings 27 and 33, and the right is reserved to make such changes and alterations as fairly fall within the scope of the appended claims.

Having thus described my invention, what 10 I claim as new and desire to secure by Letters Patent, is—

1. In a device of the class described, a frame, a spindle journaled therein, a clutch member secured to the spindle, a coöperating 15 drum clutch member loosely mounted on the spindle, a clutch actuating device pivotally mounted on the frame, and having a plurality of arms, one of which arms is adapted to engage the drum clutch member 20 and move the same into engagement with the spindle clutch member, a flexible element adapted to be wound on the drum and to engage an arm of the clutch actuating device whereby upon movement of the flexible 25 element to unwind it from the drum, the clutch actuating device will be operated to engage the clutch members and rotate the spindle in one direction, and means to rotate the drum clutch member in the opposite 30 direction to rewind the flexible element on the drum.

2. In a device of the class described, a frame, a spindle journaled therein, a clutch member secured to the spindle, a coöperating 35 drum clutch member loosely mounted on the spindle, a clutch actuating device comprising a slidable plate having means to engage a drum clutch member and move the same into operative engagement with the 40 spindle clutch member, a flexible element adapted to be wound on the drum and to engage a portion of the slidable plate whereby upon movement of the flexible element in one direction, said clutch actuating device 45 will be operated to move the clutch members into engagement to rotate the spindle in one direction, and means to rotate the drum clutch member in the opposite direction to rewind the flexible element thereon.

50 3. In a device of the class described, a frame, a spindle journaled therein, a plurality of clutch members secured to the spindle, each of said clutch members having associated therewith a loosely mounted drum 55 clutch member adapted to rotate the spindle in opposite directions, and a clutch actuating device adapted to engage each of the drum clutch members to move them into engagement with the spindle clutch members, and a flexible element adapted to be 60 wound on each of the drum clutch members.

to have engagement with its respective clutch actuating device, whereby upon the movement of a flexible element in one direction it will serve to rotate its drum and actuate 65 its respective clutch actuating device to rotate the spindle in the direction of movement of the drum, and means connected with the drum clutch members to rotate them in a direction opposite to that in which 70 they are moved by the flexible element.

4. In a device of the class described, a frame, a spindle journaled thereon, a clutch member secured to the spindle, a coöperating drum clutch member loosely mounted on the 75 spindle, a spring coiled around the spindle and connected with the drum and frame to maintain the drum clutch member separated from the fixed clutch member and to rotate the drum clutch member in one direction, a 80 flexible element adapted to be wound upon the drum and to have engagement with a clutch actuated device, whereby upon drawing upon the flexible element, the drum clutch member engages the fixed clutch 85 member and rotates the drum against the action of the spring and thereby rotates the spindle in one direction and upon the release of the flexible element the clutch members will be automatically disengaged to 90 prevent rotation of the spindle in an opposite direction.

5. In a device of the class described, a frame having a spindle journaled therein, a clutch member secured to the spindle, a 95 coöperating drum clutch member loosely mounted on the spindle and adapted to be reciprocated thereon toward a fixed clutch member, a clutch actuating device mounted on the frame and comprising a slidable plate 100 having an arm to engage the movable drum clutch member for moving the same into operative engagement with the spindle clutch member, and a flexible element extending through the frame and between a portion of 105 the slidable plate and the frame and thereafter wound on the drum, whereby upon drawing upon said flexible element in one direction, said clutch actuating device will operate to move the clutch members into engagement to rotate the spindle in one direction, and means carried by the spindle to rotate the drum clutch member in the opposite direction to rewind the flexible element 110 thereon.

115 In testimony whereof, I affix my signature, in presence of two witnesses.

CLARENCE W. FULLER.
